CLAIM

The ornamental design for a golf club head, as shown and described.

DESCRIPTION

FIG. 1 is a perspective view of my golf club head; FIG. 2 is a perspective view of my golf club head, the shaft and grip shown in phantom;

FIG. 3 is an enlarged front perspective view thereof;

FIG. 4 is an enlarged right side elevational view thereof;

FIG. 5 is an enlarged left side elevational view thereof;

FIG. 6 is an enlarged front elevational view thereof;

FIG. 7 is an enlarged rear elevational view thereof;

FIG. 8 is an enlarged top view thereof; and,

FIG. 9 is an enlarged bottom view thereof.

The broken line showing of the shaft and handle is for illustrative purposes only and forms no part of the claimed design.
